METHOD OF SEISMIC PROSPECTING

William E. Pugh, Tulsa, Okla., assignor to
Seismograph Service Corporation, Tulsa, Okla.,
a corporation of Oklahoma -

Application September 22, 1942, Serial No. 459,325

4 Claims. (Cl. 181—0.5)

This invention relates generally to the art of geophysical prospecting and more particularly to a method for conducting a continuous profile survey of the substrata of the earth's surface.

In order to obtain the data necessary from which a continuous profile of the substrata of the earth can be produced, it has been customary heretofore to record seismic waves which have been reflected from the interfaces of the substrata at detecting stations spaced at equal intervals throughout the length of the entire traverse. The detecting stations are usually divided into equal groups to form spreads and the waves detected at each group of stations recorded on a single seismogram in coordination with time. At each spread two records are made which represent waves originating at shot points that are equally spaced from the opposite ends of the spread. This procedure was thought necessary to obtain 100% continual subsurface control.

The instant invention is directed to a method of conducting a continuous profile of the substrata of the earth's surface for a 100% continuous subsurface control from only 50% of surface spread coverage and which will utilize one-half the normal number of geophone set-ups for any given traverse distance.

Other outstanding advantages of the present invention over those practiced heretofore are: Acceleration of field operation, deep penetrating weathering control, elimination of spread and variable velocity effects and minimized calculation errors.

Other advantages of the present invention will become apparent from the following detailed description, when considered with the accompanying drawings in which:

Figure 1 is a diagrammatic view illustrating the positioning of detectors and sources of elastic waves along a traverse in accordance with the teaching of the instant invention;

Figures 2a and 2b are illustrations of weathering data sheets;

Figure 3 is an illustration of a dip calculation sheet; and

Figure 4 is an illustration of a recapitulation sheet.

Referring to the drawings, particularly Figure 1, this method of obtaining a 100% continuous profile of the substrata by the use of one-half the usual number of geophone set-ups for any given traverse is described in detail for a twelve-trace unit using a shot point interval of, for example, 1320 feet. The geophones in each

spread are located at detecting stations that are spaced at 110-foot intervals with the first geophone 110 feet from the shot point in the direction of traverse and the last, or No. 12 geophone at 1320 feet from the shot point and offset 25 to 50 feet at right angles to the line passing through the shot point position and the stations in the spread.

Assuming the geophones to be in the spread 2 position, records will be obtained from shot points S. P. 2 and S. P. 3. Then the No. 12 geophone at S. P. 4 is moved to S. P. 3 and records obtained from shot points S. P. 4 and S. P. 5. The geophones are then moved to spread 15 and the same procedure follows. In some areas it may be more desirable to use a geophone at each end of the spread. This may be accomplished by placing the geophones at 120-foot intervals, in which case it will not be necessary 20 to move a geophone after the first two shot point records are obtained.

A constant shot point interval should be used. When it becomes necessary to alter the distance at any point, it is desirable that the odd interval 25 distance be placed in the gap between geophone spreads. Thus, a constant spread distance will be maintained for the interlocking long spreads. This, however, is not necessary for if a change 30 in the geophone spread cannot be avoided, the calculation of the results can readily be changed to compensate for this change in spread. In some areas of erratic weathering, it may be advisable to place the odd interval in the geophone spread position. This will allow equivalent 35 penetration for the long weathering shots.

Where the survey is conducted in an area of continuous reflecting horizons, two shot holes should be used at alternate successive shot point locations. The locations at which two shot holes 40 are necessary are those used for the long spread shots before they are used for the short spread shots. In this manner it will be possible to measure shot hole "lag" or "fatigue," such as 45 usually occurs on the Gulf Coast. If the stepout calculation method is used, it is not necessary to measure this lag, but if the data is to be used for positive continuous control, some means of measuring the lag is required.

50 A 24-trace recording unit may be used in this method to further expedite and simplify the field operations. Using 12 traces for each adjacent pair of geophone spreads, the long and short spreads may be recorded simultaneously from each shot point. This procedure will also elimi-

nate the need for extra shot holes to provide a measure of lag.

The calculation of the weathering correction for this method involves only the determination of relative weathering differences between respective geophones. When used for continuous profiling, it will be necessary to extend this weathering calculation to obtain absolute values, or an uphole correction system may be used for the geophones adjacent to the shot points.

Sample weathering computation sheets are shown in Figures 2a and 2b. Figure 2a assumes a horizontal surface with no elevation changes. I_1 and I_2 are the recorded intervals between successive first breaks, while t_1 and t_2 are the recorded times. The smallest summation Et is used as the base and $2Wr$ represents two times the relative weathering variation. With the assumed conditions of horizontal surface, $V_0=2000$ ft./sec. and $V_e=6000$ ft./sec., the combined weathering and elevation correction (t corr.) is arrived at immediately by the relationship

$$t \text{ corr.} = \frac{2Wr}{3}$$

For other velocity relationships a different formula may be calculated.

Figure 2b shows the computation when there are elevation differences on the surface. The elevations are reduced to a relative difference with respect to the same geophone used for the zero weathering. The base of the relative weathering is calculated using $V_0=2000$ ft./sec. and from this the relative elevation correction in time (t_e) is computed using $V_e=6000$ ft./sec.; t_e is opposite in sign to the relative base of the weathering. Wr and t_e are then combined to obtain the relative weathering and elevation correction, t corr. The actual numerical values will of course depend upon the V_0 and V_e for the particular area.

From the calculated t corr. values, the weathering correction to be applied to the traces used in the dip calculations is obtained. Thus, on Figure 2a the 1-11 correction is +.007, the 2-10 correction is +.007, the 3-9 correction is +.005, etc.

At the top of the weathering data sheets are placed the shot point numbers from which the refraction breaks were obtained while on the sides, in the distance rows, are placed the shot point numbers immediately adjacent to the geophone spread. The first shot point number of each pair represents the direction of traverse. Shot point numbers on records and data sheets are designated by the prefix c for short shots and L for long shots.

Where the weathering conditions are not particularly erratic, the short spread first breaks may be used for weathering calculations. This is recommended only when the long spread first breaks are not satisfactory.

Refraction breaks can often be counted more accurately by utilizing the trough after the first break and by counting intervals between successive troughs. Care should be exercised in noting frequency changes along the spread. That is, there is sometimes a change in time interval from first break to first trough between the first and last geophones. This time change must be corrected unless a similar change occurs on the interlocking profile.

The fundamental principle involved in this method of dip calculations is that, under similar conditions of velocity, the variation in reflection

times (after correcting for weathering and elevation) between any two geophones is a function of the dip of the reflecting horizon. Thus, for any given spread distance, the difference in reflection times (stepout) between any two geophones will remain constant for a horizontal bed. This constant will be designated as the normal stepout or Δtn . It follows that for a profile in direction of down dip the stepout will be greater than Δtn and for a profile in direction of up dip, the stepout will be less than Δtn .

For a special case in which the reflecting horizon is considered as a plane surface let

tr_1 =the reflection time to the first geophone

tr_m =the reflection time to the m th geophone.

Then $tr_m - tr_1$ =the stepout Δ_1 in the direction 1 to m . Similarly, reversing the direction of shooting, and maintaining the same shot distance as in normal continuous profiling

$tr_1 - tr_m$ =stepout Δ_2 in the direction m to 1

Δw =difference in weathering between 1 and m

$\Delta_1 = \Delta tn + \Delta t\alpha$ (due to slope of reflecting horizon) + Δw

$\Delta_2 = \Delta tn - \Delta t\alpha - \Delta w$

$\Delta_1 - \Delta_2 = 2\Delta t\alpha + 2\Delta w$

If the weathering influences are corrected then $\Delta_1 - \Delta_2 = 2\Delta t\alpha$ in which $2\Delta t\alpha$ is a direct measure of the dip or difference in time datum in the subsurface between the No. 1 and No. m geophones

It will be obvious from a study of Figure 1, that by a proper arrangement of geophone spreads and shot points, one obtains a similar subsurface control as at E and A.

Since Δtn is also the spread correction, the latter is eliminated in $\Delta_1 - \Delta_2$. Also it is seen that since the velocity may be considered as a constant locally, areal velocity variation effects have been reduced to a minimum by the simple device of subtracting from each other the stepouts observed continuously in two directions.

In other methods of dip shooting in which discontinuous one-directional observations of stepouts are made, it is necessary to know the absolute velocity values before dips can be calculated. For absolute depth maps, it is, of course, necessary to have velocity information, but by this method, preliminary time maps may be constructed as the work progresses. If desired, these may later be changed to absolute depth maps when velocity information becomes available.

To apply the above principles to the field procedure, refer to Figure 1. Recording at spread 2 from shot point 3, the stepout Δ_1 for the subsurface at B can be measured, and recording at spread 2 from shot point 4, the stepout Δ_2 for the subsurface at C can be measured. Then, using the proper algebraic signs $\Delta_1 - \Delta_2$ represents the dip in the direction 3-4 for the subsurface B+C. This dip is converted by the necessary factor K to represent the dip for the distance between shot points. For the conditions assumed in the diagram using the No. 1 and No. 11 geophones in which No. 1 is at 110 feet and No. 11 is at 1210 feet from the shot point, the subsurface coverage for $\Delta_1 - \Delta_2$ is 1100 feet and the factor K to convert to 1320 feet coverage is 1.2.

By the expedience of the long spread shots, the dip for the gap between the successive geophone spreads may be determined. Recording again at spread 2 from shot point 5 a measure of the stepout Δ_2 for the subsurface at D can be

made. Then moving geophones to spread 3, one can record from shot point 4 and measure the stepout Δ_1 at F. Here again $\Delta_1 - \Delta_2$ represents the dip in the direction 4-5 for the subsurface D+F. The dip is now converted to 1320 feet coverage by the necessary factor.

It will be seen that as the shooting progresses along the line of traverse, an approximate 100 per cent continuous control has been maintained.

The algebraic sign of $\Delta_1 - \Delta_2$ will show the direction of dip along the line of traverse. If $\Delta_1 - \Delta_2$ is plus the dip is down, if minus, the dip is up in the direction of traverse.

In practice, the 1 to 11 and the 2 to 10 trace stepouts are usually averaged together for each directional stepout determination.

Referring to Figure 3, which is the preliminary calculation sheet and contains a full tabulation of reflection information obtained from each record, t_1 is the time of the first trace; Δ_1 the reflection stepout from No. 1 to No. 11; Δw the combined elevation and weathering correction (t corr.) for 1-11 obtained from the weathering calculation; Δ_{1c} is the summation of columns 2 and 3; K the factor to convert 1-11 coverage to 1320 feet or to the shot point interval; and $K\Delta_{1c}$, final corrected stepout or column 4 times K , Δ_2 is the stepout from No. 2 to No. 10; Δw the 2-10 relative weathering (t corr.); and the remainder of the items are self explanatory. $AvK\Delta_{1c}$ is the average of the 1-11 and 2-10 $K\Delta_{1c}$'s.

The elimination of one source of error can be obtained by the use of tabulation charts for the conversion of $\Delta_1 C$ to $K\Delta_{1c}$. If the record information is good, the $K\Delta_{1c}$ (1-11) and the $K\Delta_{1c}$ (2-10) should check reasonably well. If not, an error may be expected in the weathering, in the instruments or in the readings (very rarely due to subsurface). If the 1-11 and 2-10 Δ 's do not check, a new calculation using another pair of traces such as 3-9 may help to decide which of the original two is correct. If the latter check does not help, and the profile is in an important part of the area from a structural point of view, the same depth points can be repeated by moving the geophone spread from the original position to the gap position. In this manner, dip information from the same subsurface can be obtained at an entirely new geophone position.

The only computing digits necessary on the records are the first break counts and, for reflections, the first trace count and the stepout counts for the traces used. In making up the dip calculation sheets or, in other words, in making reflection picks and stepout counts, the weathering information should be considered. When stepouts of traces used for Δ_1 and Δ_2 do not fit the weathering, records should be questioned and studied carefully. The observer should watch for bad traces particularly Nos. 1, 2, 10 and 11. Quite often, a lag or lead will be caused by a defective geophone.

Reflection picks should be made on each profile separately, disregarding the interlock record (unless continuous horizons are being followed). This is important since identical time interlock picks will often result in poor to bad picks being made on one or both records. It is not necessary for dip calculation by $\Delta_1 - \Delta_2$ that the tr 's be identical. It is merely necessary that they be reasonably close. The latter qualification may

be evaluated by a consideration or study of the normal Δt curve.

Second record checks should always be made. If there is any variation in count for the same reflection pick, either the best character pick should be used or if both picks are equally good, an average taken. For best results, it is recommended that the same interpreter make picks on all records for one profile, these later to be checked arithmetically by another computer and reviewed by the interpreter.

From the preliminary calculation sheet, the computations are transferred to the final recapitulation sheet, see Figure 4. Tr and tr_2 are taken from the calculation sheet and averaged to obtain column 3 ($Av Tr$). $Av\Delta_1$ and $Av\Delta_2$ are combined to give

$$\frac{\Delta_1 - \Delta_2}{2}$$

which represents the dip component for 660 feet of subsurface. Changes in spread distances should be noted and the calculations revised to fit same. The Δ 's and Δ 's must represent stepouts between the same absolute geophone distances or else the operation of $\Delta_1 - \Delta_2$ will not eliminate the spread correction.

Column 9 contains the quantity

$$\frac{\Delta_1 + \Delta_2}{2}$$

which represents the normal Δt or Δtn . These latter values are tabulated as the work progresses. A reasonably large number of these Δtn values when averaged and plotted against time will furnish an excellent normal Δt curve for the particular area. This curve may then be used to calculate velocities, dips from single direction stepouts and often to furnish a good check against erratic dips. For example, the reflection tabulated on Figure 4, Profile 4LE-5LW, $Av Tr$ 1.585, shows a dip which is not consistent with the remainder of the dips for that particular determination. The

$$\frac{\Delta_1 + \Delta_2}{2}$$

or Δtn value for this reflection is .043, whereas the Δtn from the Δt curve is .038. If a reliable Δt curve has been obtained for the area, then these dips are either unreliable or do not represent dips from a continuous subsurface. Such dips should be plotted separately as single dips and subjected to additional study. Note that several dips have been calculated from the single direction stepout using the Δtn values taken from the Δt curve. These dip values are placed in column 14.

In the tabulation of the

$$\frac{\Delta_1 + \Delta_2}{2}$$

values, the long and short spread values are tabulated independently. One method of tabulation is as follows:

Separate the time scale into units of 0.2 second. Tr 's and Δt values between 1.000 and 1.199 are tabulated in one set; between 1.2 and 1.399 in the next, etc. Then, the average of each tabulation will give an ordinate and abscissa of the tr and Δt respectively. The Δt curve should be drawn to furnish a smooth average curve for the data at hand. Log-log paper is recommended for this plotting. Usually, the larger the number of tabu-

lated values, the better the individual points will approach a smooth curve.

Average velocities are calculated from the

$$V_a = \sqrt{\frac{d_2^2 - d_1^2}{\Delta t n (2t + \Delta t n)}}$$

in which d_1 and d_2 are the distances to the beginning and end of the geophone spread. $\Delta t n$ is read from the Δt curve at the time t .

In column 13, T_{12} is the sum of columns 3 and 11, and represents the computed time for the 12th trace for purposes of plotting. Practically, however, plotting can be simplified by using the time $A_v T_r$ and constructing the dips by slope.

After the dip recapitulations have been computed, the dip components are plotted in cross section. The

$$\frac{\Delta_1 - \Delta_2}{2}$$

values are plotted for 660 feet of subsurface coverage with the midpoint at the center of the shot point interval.

It is recommended that when the single dip determinations are plotted on the cross section, some method of plotting be used which will distinguish the single dip values from the

$$\frac{\Delta_1 - \Delta_2}{2}$$

dip values since the latter should ordinarily be given the greater weight.

Phantom dips are then obtained by averaging the several picks at various levels depending upon the results and the structural peculiarities of the area under survey.

The recommended grading of reflection picks utilizes four grades; good, fair poor and questionable. Then in obtaining average dips, the use of respective weights of 4, 3, 2 and 1 should approach the best available average. In this connection, however, much depends upon the results at hand, and it is entirely possible that good looking reflection picks are fallacious. For instance, good reflections may be had from lithologic or stratigraphic lenses whose subsurface attitude is different from the overall geologic structure. Normally, when the large majority of fair to good picks suggest a certain dip, other picks at variance to the majority may usually be disregarded without further consideration.

When individual dips approach the magnitude of 100 feet or more to the mile, the horizontal displacement of the depth points should be taken into account when the dips are plotted in cross section. Each pair of adjacent phantom dips, one obtained from long spread records, the other from short spread records, are averaged to obtain the dip component which is plotted for 660 feet of subsurface with the midpoint at the shot point, see Figure 1. It should now become apparent that by using

$$\frac{\Delta_1 - \Delta_2}{2}$$

and by averaging adjacent dip determinations for shot point dip components, the effect of error will be reduced. The weathering influence in the

short spread dip determination is cumulative, hence by using the determination for 660 feet rather than 1320 feet, the error is reduced by 50 per cent. The Δ_1 's and Δ_2 's obtained from the long spread records do not necessarily have cumulative weathering effects because they are obtained from two different geophone spreads. Such a system of averaged computations should normally tend to reduce inherent errors to a minimum.

I claim:

1. A method of seismic surveying that comprises the steps of dividing a traverse into equal intervals, locating in alternate intervals a plurality of equally spaced detecting stations to form alternate spreads, creating seismic waves at both ends of each spread and also at the far extremity of the adjacent interval at opposite ends of the spread, separately detecting at each spread the waves which have been so created at each point, amplifying and recording the detected waves in coordination with time.

2. A method of obtaining data for a continuous profile of a subsurface formation that comprises the steps of dividing a traverse into equal intervals, locating a plurality of equally spaced detecting stations along alternate intervals to form alternate spreads, creating seismic waves at both ends of each spread and also at the far extremity of the adjacent interval at opposite ends of the spread, separately detecting the waves after they have been so created and which have been reflected from the interfaces of the substrata, amplifying and recording the detected waves in coordination with time.

3. The method of profiling a subsurface formation with 100 per cent subsurface control that comprises the steps of dividing the traverse along which the profile is to be made into equal intervals, locating along alternate intervals equally spaced detecting stations, the detecting stations in each interval forming a spread, creating seismic waves at both ends of each spread and also at the far extremity of the adjacent interval at opposite ends of the spread, detecting and recording on separate records at the first spread the waves which have been so created, advancing along the traverse to the next spread and repeating the operations until the entire traverse has been covered.

4. The method of profiling a subsurface formation with 100 per cent subsurface control that comprises the steps of dividing the traverse along which the profile is to be made into equal intervals, locating along alternate intervals equally spaced detecting stations, the detecting stations in each interval forming a spread, creating seismic waves at both ends of each spread and also at the far extremity of the adjacent interval at opposite ends of the spread, detecting and recording on separate records at the first spread the waves which have been so created, and which have been reflected from the interfaces of the substrata, advancing along the traverse to the next spread and repeating the operations until the entire traverse has been covered.

WILLIAM E. PUGH.
